UNITED STATES PATENT OFFICE.

LOUIS L. GAGNON, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

OPHTHALMIC MOUNTING.

Application filed April 5, 1926. Serial No. 99,853.

This invention relates to an improvement in ophthalmic mountings and has particular reference to an improved adjustable bridge and arm construction for the same.

5 The principal object of this invention is to provide adjustable means for the lens and guard connections of an ophthalmic mounting whereby the lenses may be adjusted to be positioned before the eyes and whereby 10 the guards may be independently adjusted for their proper relation with the nose of the wearer.

Other objects of the invention will become apparent from the following description taken in connection with the accompanying drawings, and it will be apparent that changes and modifications in the arrangement and construction of the parts may be made without departing from the 20 spirit of the invention as expressed in the accompanying claims, the preferred form only of the invention having been shown by way of illustration. I, therefore, do not wish to be limited to the exact details 25 of construction and arrangement of parts shown.

Referring to the drawings in which similar characters of reference denote corresponding parts throughout:

30 Figure 1 is a perspective view of the bridge and guard construction and its attachment to the lens connecting means;

Figure 2 is a rear elevation of Figure 1; Figure 3 is a side elevation of Figure 2;

35 Figure 4 is a partial plan view of a modified form of the invention showing a different arrangement of the loops connecting the lens attaching means and the guard means, respectively.

40 Referring to the drawings, a pair of lens connecting clips 1 are connected by a bridge member 2 having at each end a forwardly extending loop portion 3 and a downwardly extending portion 4 which is attached to the

45 lens holding clip 1; also on the respective ends of the bridge 2 is a second loop portion 5 which extends rearwardly and downwardly to a forwardly extending loop portion 6 and a forwardly extending arm 7 to which is secured the nose guard 8.

In Figure 4 I have shown a modification in which the adjustable loops 6 and 3 are

made in an S shape having one end attached to the lens clip 1 and the other end attached to the nose guard 8 and the bridge 2 secured 55 at the point 9. The adjustments of this modification are practically the same as those of the construction shown in Figure 1.

The method of operation is as follows: The lens clips 1 may be adjusted in and out 60 and up or down by bending the loop portion 3. In this way the distance between the lens clips 1 may be regulated as well as its position vertically, and also the lens clips 1 may be adjusted to a nearer or farther approach to the guard 8 by bending the loop portion 3. The nose guards 8 may be adjusted in or out, up or down, or angled by bending the arm 5 and the loop portion 6. This allows the bridge to be positioned 70 on the nose up or down, in or out, or angled by the bending of the arm 5 and the loop 6. The guard 8 may also be approached towards or moved away from the lens clips 1 by adjustment of the said arm 5 and loop 6. 75

The adjustments of the loop 3 and the loop 6 may be made independently of each other. Therefore, the lens clips 1 may be adjusted without disturbing the adjustment of the guards 8 and the guards 8 may be 80 adjusted without disturbing the adjustment of the lens clips 1. This construction, therefore, allows a double adjustment to adjust the guards to the nose on one hand and the lens clips to the eyes or face on the other 85 hand, whereby the mounting can be perfectly adjusted to all the facial requirements of the wearer.

It has been found in practice that there are many variations in the facial characteristics of people, and it is, therefore, very difficult to adjust a mounting to give the proper pupillary distance, the proper height, the proper angle of the guards on the nose, and the proper adjustment in or out or side- 90 wise.

From the foregoing it will be seen that I have provided simple, efficient and inexpensive means for carrying out the various adjustments required in the fitting of an 100 ophthalmic mounting, well adapted to carry out all the objects of the invention.

Having described my invention, I claim:

1. In a device of the character described

in combination with means for holding a pair of lenses, a bridge member connecting the lens holding means comprising a central bridge portion and bifurcated terminal loop portions, one bifurcation extending rearwardly and then forwardly and the other bifurcation extending forwardly, downwardly and rearwardly, a nose guard secured to the forwardly extending portion of the first bifurcation and a lens holding means secured to the rearwardly extending portion of the other bifurcation.

2. In a device of the character described

in combination with means for holding a pair of lenses, a bridge member connecting the lens holding means comprising a central bridge portion and bifurcated terminal loop portions, one bifurcation extending rearwardly and then forwardly and the other bifurcation extending forwardly and then rearwardly, a nose guard secured to the forwardly extending portion of the first bifurcation and a lens holding means secured to the rearwardly extending portion of the other bifurcation.

LOUIS L. GAGNON.
